UNITED STATES PATENT OFFICE.

EMERSON MCKENNEY, OF BANGOR, MAINE, ASSIGNOR, BY DIRECT AND MESNE ASSIGNMENTS, TO MCKENNEY-CARR COMPANY, A CORPORATION OF MAINE.

PRUNING-SHEARS.

14,614.

Specification of Reissued Letters Patent. Reissued Mar. 18, 1919.

Original No. 1,173,527, dated February 29, 1916, Serial No. 52,207, filed September 23, 1915. Application for reissue filed June 30, 1917. Serial No. 178,037.

To all whom it may concern:

Be it known that I, EMERSON MCKENNEY, a citizen of the United States, residing at Bangor, in the county of Penobscot, State of Maine, have invented a new and useful Pruning-Shears, of which the following is a specification.

This invention relates to improvements in pruning shears, particularly that class in which the movable cutting blade is operated by a rack and pinion, and has for its object to provide a comparatively simple device of this character which will readily and effectively accomplish the purposes for which it is designed.

Another object of my invention is to provide pruning shears provided with removable cutting blades of such formation as to facilitate a deep clean cut into the branch without bruising or injuring the same.

Still another object is to provide a device of this character whose cutting blades have stops formed thereon for limiting the movement of one toward the other so as to prevent dulling of the cutting edges of the said blades by coming in violent contact with one another.

Still a further object of my invention is to provide pruning shears whose movable cutting blade is readily removable from the rack bar of the device.

With these and other objects in view my invention resides in the novel features of construction, combination and arrangement of parts as will be hereinafter more particularly described and claimed.

In the accompanying drawings—

Figure 1 represents a side elevation of a pair of pruning shears embodying my improved features of construction;

Fig. 2 is a front edge view thereof, with the cutting blades arranged in contact with one another; Fig. 3 is a vertical section on line 3—3 of Fig. 4;

Fig. 4 is a central vertical longitudinal section on line 4—4 of Fig. 2;

Fig. 5 is a similar view but showing the cutting blades spaced apart;

Figs. 6 and 7 are horizontal sectional views on the lines 6—6 and 7—7 of Fig. 4;

Fig. 8 is a side elevation of the movable cutting blade and the rack arranged in juxtaposition.

Referring to the drawings wherein similar

reference characters designate corresponding parts throughout the several views, 1 indicates broadly a housing adapted to inclose the movable cutting blade and the operating mechanism therefor.

Formed integrally with one end of this 60 housing 1 is a tubular shank 2 adapted to be secured to the end of a suitable handle or pole 3, while from the opposite end of said housing 1 a shank 4 projects, said shank having its free end extended laterally to provide 65 an arm 5. This arm 5 is provided on its lower edge with a groove 6 which communicates with a similar groove 7 formed in the adjacent edge of said shank 4, said grooves being adapted to receive the edges of a removable stationary cutting blade 8.

The groove 7 communicates with a suitable guide passage 9 formed through the housing 1 at its forward portion, said passage being adapted to receive a movable 75 cutting blade 10. This movable cutting blade 10 is provided with a shank 11 formed on its lower edge which is adapted to be inserted in a groove 12 formed in one edge of a rack bar 13, said rack bar having 80 formed integrally with its lower end an ear 14 for a purpose to appear. The rack bar 13 is preferably though not necessarily tapered from its lower toward its outer end, thus causing the toothed edge thereof to be 85 inclined. The gear sector 17 adapted for coaction with the said rack bar is also of a peculiar shape from its pivot to the teeth and meshes with the rack teeth as the sector is moved to the right about its pivot. This 90 arrangement, including the initial position and subsequent movement of operating arm 18 as indicated in Figs. 1 and 4, has the effect of giving the device increasing leverage and cutting power as the blades move 95 toward each other through the limb which is being severed. The shank 11 of this cutting blade 10 is provided with a notch 15 which is adapted to coact with a stop 16 forward in said groove 12. When these two parts 100 of the device are assembled, as shown in Fig. 5 of the drawings, with the stop 16 in the slot 15, any longitudinal movement of the parts relative to one another will be prevented. Lateral movement thereof is also 105 prevented by the gear sector 17 which coacts with the rack 13 and holds the aforesaid parts in contact with the front wall of the

guide passage 9. This gear sector 17 is formed integrally with one end of an operating arm 18, while at the other end of said arm is formed an eye 19 in which a suitable 5 operating cable 20 is adapted to be placed. The member 17 is formed with an eccentric pivot hole 21 which is adapted to align with similar holes 22 formed in the walls of the housing 1, and receive therethrough a pivot 10 pin 23. When in normal position, the operating arm 18 is positioned as shown in Fig. 1, with its forward edge abutting a stop 24 formed on the edge of the housing member 1, but when this arm is moved 15 downwardly toward the position in which it will extend in a line at right angles with the line of the blade or cutting knife actuation, as in Fig. 4, movement, with constantly increasing power, will be imparted to the gear 20 and rack to raise the movable cutting blade into the position shown in Figs. 2 and 4.

Both the stationary cutting blade 8 and the movable blade 10 have a gradually tapering formation from approximately the 25 base to the cutting edge thereof and are provided along one edge with a thickened portion 25 and 26 respectively, which is adapted to be received in the groove 7 formed in the shank 4. The inner ends of 30 these thickened portions are squared to provide stop members 27 which are adapted to abut when the cutting blades are moved into final cutting position. By providing this stop means the cutting edges of the blades 35 will be prevented from coming into violent contact with one another and dulling the same.

The stationary cutting blade is formed with a hole 28 through its upper portion for 40 register with the holes formed in the arm 5 and is adapted to receive therethrough a screw 29 for holding it in rigid position in the grooves 6 and 7.

The aforesaid ear 14 formed on the rack 45 bar 13 is adapted to receive one end of a spring 30 whose opposite end is secured to the eye 31 so as to normally hold the cutting blades in spaced relation to one another. It will thus be seen that this spring will always 50 move the cutting blades apart when the cable secured to the operating arm 18 is released.

By providing removable cutting blades, 55 said blades may be conveniently sharpened at any time or replaced, when worn out, by new blades. Particular emphasis is laid on the stop members provided on these cutting blades as well as the means for securing the removable blades in operative position in 60 the device.

From the foregoing description of the construction of my improved pruning shears, the manner of applying the same to use and 65 the advantages thereof will be readily understood, and it will be seen that I have

provided a simple and inexpensive, yet efficient device of this character for carrying out the objects of the invention; namely the long gradual tapered formation of the cutting blades from near the base thereof to the 70 cutting edge, thereby securing a clean cut through the wood without crushing the wood and bruising the bark and the eccentric relation of the lever fulcrum with respect to the blade carrying member combined with 75 the arrangement of this lever, so that it shall approach the position in line at right angles with the line of blade actuation, to increase the cutting power as the blades approach the meeting point, where the maximum resistance to the cutting operation is 80 presented by the object operated upon.

While I have particularly described the elements best adapted to perform the functions allotted to them, it is obvious that various changes in form, proportion, and in the minor details of construction may be resorted to within the scope of the appended claims without departing from the spirit or sacrificing any of the principles of the invention. 90

Having described my invention, what I claim is:—

1. In a pruning device, a housing having a longitudinal guide passage, a handle at one end of said housing, a shank extending from the other end, a stationary blade carried by said shank, a movable blade carrying member slidable in said guide passage, a blade on said member for coaction with the stationary blade, a rack bar contacting with said member, means for preventing longitudinal shifting of said rack relative to said member, a gear sector for coaction with the rack, said sector holding said rack bar and 100 said member in cooperative engagement, whereby the latter is raised or lowered upon movement of the former, and means for operating said gear sector. 105

2. In a pruning device, a housing having 110 a longitudinal guide passage, a handle at one end of said housing, a shank extending from the other end, a stationary blade carried by said shank, a movable blade slidable in said guide passage, and coacting with the stationary blade, a shank extending from said movable blade within the guide passage, a rack bar having a groove in one of its longitudinal edges receiving one longitudinal edge of the shank, means for preventing longitudinal shifting of said rack relative to said member, a gear sector for coaction with the rack, said sector holding said rack bar and said shank in cooperative engagement, whereby the latter with its 115 blade is raised or lowered upon movement of the former, and means for operating said gear sector. 120

3. In a pruning device, a housing having 125 a longitudinal guide passage, a handle at 130

- one end of said housing, a shank extending from the other end, a stationary blade carried by said shank, a movable blade carrying member slidable in said guide passage, 5 and having a notch in one of its edges, a blade on said member for coaction with the stationary member, a rack bar contacting with said member, a stop carried by the bar for engagement with said notch to prevent 10 longitudinal shifting of the parts, a gear sector for co-action with the rack, said sector holding said rack and said member against lateral movement, whereby the latter is raised or lowered upon movement of the 15 former, and means for operating said sector.
4. In a pruning device, a housing having a longitudinal guide passage, a handle at one end of said housing, a shank extending from the other end, a stationary blade carried by 20 said shank, a movable blade slidable in said guide passage and coacting with the stationary blade, a shank extending therefrom within the guide passage and having a notch on one of its edges, a rack bar having a 25 groove in one of its longitudinal edges receiving one longitudinal edge of the shank, a stop within said groove engaging said notch to prevent longitudinal shifting of the members, a gear sector for coaction with 30 the rack, said sector holding said rack bar and shank against lateral shifting, whereby the latter with its blade is raised or lowered upon movement of the former, and means for operating said sector.
- 35 5. In a pruning device, the combination of oppositely acting cutting knives each having a gradually tapering formation from approximately the base to the cutting edge thereof, and means whereby a knife is moved 40 with increasing power toward the meeting point where the maximum resistance to the cutting operation is presented by the object operated upon.
6. In a pruning device, the combination of oppositely acting cutting knives, knife supporting elements, one movable with respect to the other, means for actuating the movable supporting element comprising an operating lever and a pivot support therefor, arranged and operated whereby the point of engagement between the weight arm of the lever and the movable supporting element approaches the fulcrum of the lever, and the power arm of the lever moves from a line parallel with the movement of the blades 55 and approaches a line at right angles with said line of movement, as the knives approach the meeting point.
7. In a pruning device, the combination of oppositely acting cutting knives, knife supporting elements, one movable with respect to the other, means for actuating the movable supporting element comprising a rack, a co-operating sector gear, having an eccentric pivot, for engaging the rack, and an 60 actuating lever connected with said gear, the parts arranged so that the point of engagement between gear and rack approaches the pivot, and the power end of the lever moves from a line parallel with the knife movement and approaches the line at right angles 70 with a line of said movement, as the knives approach the meeting point.
8. The combination of oppositely acting cutting knives each having a gradually 75 tapering formation from approximately the base to the cutting edge thereof, and means comprising an actuating lever and an eccentric actuator arranged to exert, in initial position, a minimum of power, and, in final 80 position, a maximum of power, whereby the knives are moved with increasing power toward the meeting point where the maximum resistance to the cutting operation is presented by the object operated upon.
